I. ROTH INVENTOR.

BY *Everett R. Roth*,
ATTORNEYS.

UNITED STATES PATENT OFFICE.

ISIDOR ROTH, OF BROOKLYN, NEW YORK, ASSIGNOR TO BENJAMIN & JOHNES, A CORPORATION OF NEW JERSEY.

BRASSIÈRE AND SIMILAR GARMENT.

Application filed September 12, 1924. Serial No. 737,253.

The objects of this invention are to provide an improved brassière or similar garment having at its top circumferentially elastic means for holding the garment in place on the wearer, instead of shoulder straps; to provide such elastic means which can be adjusted angularly with respect to the front portion of the garment, so as to fit the top of the same close to the wearer; to utilize for this purpose an elastic band at the back of the top of the garment, separate from the main back portion of the garment; to thus enable the top of the garment to be securely held in place on the wearer, without shoulder straps, and yet not cut into or indent the flesh so as to show a ridge above the garment, and to obtain other advantages and results as may be brought out by the following description.

Referring to the accompanying drawings, in which like numerals of reference designate the same parts throughout the several views,

Figure 1 is a view of a brassière containing my improvements, showing the same in place upon a wearer;

Figure 2 is a front view of the brassière removed;

Figure 3 is a vertical sectional view through the front and back showing the conformation of the garment to the wearer and a disposition of the elastic band at the top of the main back portion;

Figure 4 is a back view of the brassière in position upon a wearer with the elastic band sections inclined downwardly as is sometimes desirable to hold the top of the front portion of the brassière close to the wearer;

Figure 5 is a detail view of the brassière removed and with the main back portion broken away to show more clearly the inclined position of elastic band sections indicated in Figure 4;

Figure 6 is a detail view corresponding to Figure 5 and showing the elastic band parallel to the upper edge of the main back portion which is the position shown in Figures 1 and 3;

Figure 7 is a view of the brassière upon a wearer with the elastic band horizontal, as in Figures 1, 3 and 6;

Figure 8 is a view of the back portion of the brassière from the outside, and

Figure 9 is an inside view of one section of said back portion, partly broken away to show certain stiffening members.

In the specific embodiment of the inven-

tion shown in said drawings, 1 indicates the front portion of a brassière which is shown as having a lower diaphragm-supporting part 2 and an upper part 3 of softer and more yielding material, the lower diaphragm-supporting part 2 being comparatively unyielding. These parts 2 and 3 are shown extending from one side seam 4 of the brassière to the other side seam 5 and joined to each other as at the seam 6, and furthermore the entire front portion is shown given a form fit by means of seams 7, 7. However, all these detail features are immaterial to the present invention and the said front portion 1 may be of any ordinary and well-known construction.

To the opposite ends of said front portion 1 is connected a main back portion which is preferably made in two sections 8, 9 adapted to be detachably joined together at the wearer's back by any suitable means, such as hooks 10 and cooperating eyes on the other section. This back portion may be of any ordinary and well-known construction, but it is shown as not extending clear to the top of the ends of the front portion 1, and at the bottom of the garment elastic gores 11, 12 are shown between the front portion and back portion to enable the lower edge of the garment to flare slightly and conform more perfectly to the figure of the wearer. Stiffeners may be employed wherever desired, as shown at 13 and 14, and I have shown the seam 6 of the front portion 1 of the garment extended throughout the back portion, as indicated by reference numeral 15. However, it will be understood that all these detail features are immaterial to the present invention and the said back portion 8, 9 may be of any ordinary and well-known construction.

In carrying out my invention, I connect the upper parts of the opposite ends of the front portion 1 by an elastic band adapted to extend around the body of the wearer, preferably under slight tension, and adapted to be swung up or down to vary its angular relation to the said front portion when upon the wearer. That is to say, said elastic band may extend horizontally around the wearer, or substantially so, as shown in Figures 6 and 7, or it may be depressed at the middle of the wearer's back so as to draw in a more downward direction, as shown in Figures 4 and 5. Preferably, said elastic band is made in sections 16, 17 attached to the opposite ends of

the front portion 1 and adapted to be detachably connected at their meeting ends by any suitable means, such as the hooks 18 and eyes 19. It will be noted that the elastic band 5 formed by the sections 16, 17 may lie above the main back portion formed by the sections 8 and 9, or said sections 16, 17 may incline downwardly toward each other, according as the shape of the front portion of the garment 10 or the figure of the wearer, or any other cause, makes desirable in order to produce the best and closest fit of the upper portion of the garment. In this way such a fit of the upper portion of the garment is secured as suffices 15 to support the garment upon the wearer and obviate the use of shoulder straps. Furthermore, while the elastic band is at its points of connection to the front portion comparatively narrow with respect to the back portion it 20 is made wide enough so that it will draw upon a sufficient part of the top of the front portion 1 to ensure that neither the upper edge of the front portion nor said band will cut into the flesh of the wearer, but the garment 25 will lie smoothly in place upon the wearer without the formation of any visible ridge at its edge.

As already indicated, the construction and manufacture of my invention may be carried out with many modifications, by those skilled in the art, without departing from the spirit and scope of the invention, and I do not wish to be understood as restricting myself except as required by the following 30 claims when construed in the light of the prior art.

Having thus described the invention, what I claim is:

1. The combination in a brassière or the 40 like having a fabric front portion and a fabric back portion for holding the garment around the wearer, of an elastic band connected at the sides of the wearer to the ends of the upper marginal part of the front portion of the garment and adapted to extend 45

around the back of the wearer, said elastic band being at its points of connection to the front portion comparatively narrow with respect to the back portion and free to be swung upon its points of connection to the front portion 50 up and down with respect to the said back portion and draw said marginal part of the front portion close to the wearer independently of the rest of the garment.

2. The combination in a brassière or the 55 like having a fabric front portion and a fabric back portion for holding the garment around the wearer, said front portion having its upper marginal part extending upward beyond said back portion and terminating in 60 ends at the sides of the wearer, of an elastic band connecting said ends and adapted to extend around the back of the wearer, said elastic band being at its points of connection to the front portion comparatively narrow with respect to the back portion and free to be swung upon its points of connection to the front portion up and down with respect to the said back portion and draw said marginal part of the front portion close to the wearer 65 independently of the rest of the garment.

3. The combination in a brassière or the 70 like having a fabric front portion and a fabric back portion for holding the garment around the wearer, said front portion having its upper edge bowed upwardly at the middle, of an elastic band connected at the sides of the wearer to the ends of the upper marginal part 75 of the front portion of the garment and adapted to extend around the back of the wearer, said elastic band being free to be swung upon its points of connection to the front portion up and down with respect to the back portion and lie substantially in the same plane transverse to the wearer with the said upper edge of the front portion independent of the upper edge of said back portion.

ISIDOR ROTH.
